UNITED STATES PATENT OFFICE.

JOHN J. SELTENREICH, OF CHICAGO, ILLINOIS, ASSIGNOR TO NATIONAL CHEMICAL COMPANY, OF SYRACUSE, NEW YORK, A CORPORATION OF NEW YORK.

COLLAR-FORMING HEAD.

1,186,850.

Specification of Letters Patent. Patented June 13, 1916.

Application filed December 11, 1911. Serial No. 665,006.

To all whom it may concern:

Be it known that I, JOHN J. SELTENREICH, of Chicago, in the county of Cook, in the State of Illinois, have invented new and useful Improvements in Collar-Forming Heads, of which the following, taken in connection with the accompanying drawings, is a full, clear, and exact description.

This invention relates to certain improvements in collar ironing machines of the class set forth in the pending application of W. J. Quinn, #609,415, filed February 18, 1911 and the pending application of W. W. Quinn, #627,500 filed May 16, 1911, and no claim is made herein to the invention or inventions disclosed in either of the above identified applications, and refers more particularly to the steam heated heads in which the edges of the collars are adapted to be

pressed and smoothed in a manner somewhat similar to that set forth in Patent No. 792,454 issued June 13, 1905 to W. J. Quinn. The primary object is to provide means whereby the grooved portion of the head into which the collar is adapted to be pressed may be heated more uniformly on all sides of the groove. That is, at the inner and upper sides as well as the outer sides.

Another object is to provide the sheet metal lining which fits snugly in the groove with simple means for retaining it in its operative position.

Other objects and uses will be brought out in the following description:

In the drawings Figure 1 is a top plan of a pair of collar forming heads embodying the features of my invention. Fig. 2 is a front elevation, one-half in section, of the same pair of heads. Fig. 3 is a perspective view of the detached sheet metal lining.

In carrying out the objects stated, I preferably employ a pair of hollow cast metal heads —1— of substantially the same circular form and size integrally united to each other side by side and adapted to be secured by any well known fastening means to a supporting frame for coaction with the collar supporting elements not shown but with which these heads are adapted to be used as shown in the patent referred to. These heads are provided with communicating steam chambers —2— having a common inlet —3— at their junctions one with the other, said heads being also provided with

annular grooves —4— in their undersides and between the inner and outer walls of the steam chambers —2—, as best seen in Fig. 2, for receiving annular sheet metal linings —5— of different material such as copper, white metal or similar material which may be rolled or pressed to a smooth condition so as to take on a high polish with an expenditure of a minimum amount of time and labor. Each head is preferably provided with a central circular opening therethrough concentric with its annular groove —4—, one side of the opening being enlarged to form a radial recess intersecting the annular groove and communicating therewith so that the ends of the groove terminate at opposite sides of the recess to allow the tabs of the collars to enter said recess when the folded portions thereof are pressed into the groove. These sheet metal linings are V-shaped in cross section and the outer sides —6— thereof are of greater vertical depth than their inner sides —7—. Each lining is tightly fitted in the corresponding groove —4— and a portion of the inner side thereof is cut away at —8— to register with the corresponding recesses in the inner adjacent side of the head for receiving the flaps at the ends of the collar.

The outer wall of the groove —4— is provided with an inwardly projecting annular shoulder —10— located at a distance from the upper side of the groove —4— corresponding to the vertical depth of the adjacent side of the lining so as to hold said lining in place. That is, the lining is forced up into the groove —4— until its upper side engages the corresponding side of the groove, while the lower edges of the outer side of the lining which are somewhat yielding by reason of its being made of spring sheet metal, springs into place in engagement with the shoulder —10— after being slightly compressed during its insertion. The object in using this lining is to assure a perfectly smooth bearing for the edges of the collars throughout their entire lengths as it is practically impossible to obtain a perfectly smooth surface of cast metal for this purpose owing to the fact that in milling, sand holes and other flaws are more or less liable to develop, thereby producing a roughened surface which tends to mutilate rather than to smooth the edge of the collar. These collars are placed

upon a suitable form, not necessary to herein illustrate, and are pressed up into the grooves of the linings —5— under considerable pressure sufficient to smooth any 5 rough edges which may appear on the previously ironed collar and by extending the steam chamber across and to the inner and outer sides of the lining, so that portions of the chamber extend downwardly below 10 the upper return edge of said lining, the latter will be heated with greater rapidity and uniformity and will expedite the work of smoothing the rough edges and adjacent portions of the collars.

15 What I claim is:

1. A collar shaping head for collar ironing machines comprising a ring-shaped member having a circular groove in its under side and a vertical open recess in its 20 inner face extending radially to the annular groove for receiving the tabs of a collar, a substantially circular sheet metal lining fitted in the groove and having a portion of its inner side cut away to form a

recess registering with the recess in the head, 25 and interengaged parts upon the head and lining adapted to normally hold the lining in operative position.

2. A collar shaping head for collar-ironing machines comprising a hollow ring having a circular groove in its underside and a vertical open recess in its inner face extending radially to the annular groove for receiving the tabs of a collar, a circular lining of sheet metal V-shape in cross section fitted in the groove and having a portion of its inner side cut away to form a 30 recess registering with that in the head and a shoulder on the head adapted to hold the lining in operative position. 40

In witness whereof I have hereunto set my hand on this 16th day of November, 1911.

JOHN J. SELTENREICH.
